CORTLAND W. DAVIS AND FRANK R. SUNDERLIN, OF CHICAGO, ILLINOIS, ASSIGNEES
TO THE MANTLE LAMP CO. OF AMERICA, A CORPORATION OF ILLINOIS.

INSULATED VITREOUS RECEPTACLE.

1,333,795.

Specification of Letters Patent. Patented Mar. 16, 1920.

Application filed November 7, 1918. Serial No. 261,528.

To all whom it may concern:

Be it known that we, CORTLAND W. DAVIS and FRANK R. SUNDERLIN, citizens of the United States, residing at Chicago, in the 5 county of Cook and State of Illinois, have invented certain new and useful Improvements in Insulated Vitreous Receptacles; and we do hereby declare the following to be a full, clear, and exact description of the 10 invention, such as will enable others skilled in the art to which it appertains to make and use the same.

Our invention relates to insulated vitreous receptacles, objects thereof being to render 15 the containers of such receptacles immune, as far as possible, from external thermal influences, and also to shield them from blows and shocks which are incident to transportation and use. The container of the receptacle 20 is, for sanitary reasons, preferably made of vitreous material, such as glass, and a further object is, therefore, to so construct the inner parts of the receptacle that, when the container is broken, these parts may be removed therefrom and replaced by new parts. 25 The removability of the container and its associated parts admits of the restoration of the receptacle by a substitution of new parts.

Referring to the drawings—

30 1 is a non-vitreous protective jacket, preferably made of sheet metal, rolled and bent into cylindrical form, the edges of the sheet being overlapped, riveted and soldered together in a usual manner.

35 2 is an inner lining or jacket, and 3 is a silvered vitreous container, between which and the inner lining 2 is a space for the reception of a non-heat conducting filling 4, which is preferably granulated cork, although it may be composed of any suitable 40 heat insulating material. The film of silver on the container is protected by a suitable coating.

The jacket 1 is provided with a number 45 of grooves 1^a which not only strengthen said jacket but provide shock insulating spaces between it and the lining 2.

The bottom 5 of the jacket 1 is provided with a downwardly extending flange 5^a 50 which is riveted and soldered to the lower end of the jacket 1. Surrounding the lower end of the jacket 1 is a heavy metal ring 6 constituting a support for the entire receptacle.

55 An annular diaphragm 7 composed of copper, or other yieldable material, is dis-

posed between the lining 2 and the container 3, at their upper ends. This diaphragm has a cylindrical body portion 7^a, an internal flange 7^b and an external flange 60 7^c. The external flange extends downward a short distance outside the lining 2, to which it may be secured by solder, and the internal flange has a deflected edge 7^d. A collar 8, having an inwardly extending 65 flange 8^a at its upper end and an outwardly extending flange 8^b at its lower end, is secured to the neck of the vitreous container by a suitable bonding substance 9. The deflected edge 7^d of the diaphragm 7 overlaps 70 the outwardly extending flange 8^b of the collar 8 and is secured thereto by solder. The flange 8^b is V-shaped so as to constitute a gutter which assists in the soldering operation. 75

The lining 2, container 3, the filling 4, the diaphragm 7 and the collar 8, constitute a removable unit which, if necessary, may be separated from the jacket 1 and replaced by another unit. While the frangible container is so well protected by the environing parts of the device as not to be easily broken, even if the device is subjected to rough handling, it is possible that it may be broken or punctured under the severe conditions 85 which often attend transportation. For this reason the diaphragm 7 is made in such form that it may yield to external shocks without transmitting the same in any considerable degree to the frangible container 3. 90 The protective quality of the diaphragm is enhanced by making it of copper or some other yieldable substance which will become distorted by a blow, without transmitting much of the energy of the blow to the container. 95

The lining 2 is preferably made of some yieldable substance, such as thin sheet steel coated with lead or tin, the object being to admit of the withdrawal of the lining and 100 the associated parts, even though the protective jacket has become deformed to such an extent that, if made of rigid material, it would prevent the withdrawal of such lining. Should there be difficulty in removing 105 the lining by an endwise movement, the broken parts of the container and the filling may first be removed, and a suitable tool then applied directly to the lining in order to free it from any interlocking portions of 110 the protective jacket.

A shock resisting and retaining ring 10 is

secured in position by screws 10^a extending through holes in a reinforcing band 11 which encircles the upper end of the jacket 1. This shock resisting and retaining ring, 5 not only locks or secures the lining 2 and the container 3 within the protective jacket 1, but operates to relieve the container 3, to a considerable extent, from the effect of the shocks which instead of reaching it are 10 transmitted from one side of the protective jacket to the other.

The receptacle is provided with a bail 12, the ends 12^a of which are arranged to oscillate in holes formed in lugs 13 secured to the reinforcing band 11. The ends of the bail are secured by cotter pins 12^b which prevent their withdrawal from the holes in the lugs 13.

The container 3 is provided with a cover 14, the body portion of which consists of a mass of cork 14^a or any other suitable heat insulating substance. The inner face of this cover is provided with a sheathing 15 having a flange 15^a which extends upward 20 around the body of the cover and terminates in an outwardly extending flange 15^b. The cover is provided with a protective cap 15^c having a downwardly extending flange 15^d spaced apart a slight distance from the outer edge of the flange 15^b. Within and fitting the flange 15^d is a sheet metal ring 16 having a flange 16^a which is secured to the flange 15^d by solder 16^b. The space between the protective cap 15^c and the flange 15^b of the sheathing 15 is filled with cork 30 which may be a continuation of the main body of cork for the cover 14. In assembling the parts of the cover, the protective cap 14 and the sheathing 15 are forced together by any suitable means, thereby compressing the body of cork into which the flange 15^b extends. The pressure may be exerted through the ring 16 and the mass of cork which separates it from the flange 40 15^b, the soldering of the ring 16 to the flange 15^d of the cap being effectuated after the various parts are brought into proper relation to each other, so as to retain them in that relation. After the cover is thus 50 far completed, the annular space below the ring 16 is filled with cork which, when the cover is applied to the receptacle, bears upon the top of the collar 8 to thereby hermetically close the container 3. The only 55 contact between the cover and the container is, therefore, through the medium of a substance having low heat conductivity. The sheathing 15 is anchored by means of its flange 15^b in the body of cork, and is elsewhere spaced from the container. Furthermore, the flange 15^d of the protective cap 15^c is always heat insulated from the collar 8 and the container 3. It is extremely desirable, in heat insulated receptacles, to prevent the loss of even small quantities of 60 65

heat by conduction, since a gradual loss of heat, even though restricted, will in the course of a relatively short time materially reduce the temperature of the container and its contents. The under side of the 70 sheathing is concaved, as shown, so that liquid contents of the container when splashing about within the same may be deflected away from the space between the protective cover and the container. 75

The protective cap is secured in position by a locking device 17 consisting of a link 17^a and a lever 17^b oscillating on a pivot 17^c secured to a lug 17^d. A headed pin 18 secured to the receptacle is adapted to be 80 engaged by the link 17^a. The lever 17^b is bent at right angles so that its free end 17^e may rest upon the top of the cover when the lever 17^b is actuated.

The inner lining 2 is provided with an internal seat 19 sustaining a brace 19^a having a diagonal disposition to prevent the inner parts of the receptacle from moving endwise within said jacket. 85

The entire receptacle is closed by a cover 90 20 having a flange 20^a snugly fitting over the reinforcing band 11, the edge of said flange being provided with a bead 20^b with which a pivoted clamp 21 is adapted to engage. The clamp 21 has an inside groove 95 21^a which is adapted to fit said bead 20^b. The pivot of the clamp 21 is formed by headed rivets 22 which loosely fit openings 22^a in the lower end of the clamp. A bolt 100 23, fixedly secured to the reinforcing band 11 and threaded at its outer end, is engaged by a thumb nut 24 by means of which said clamp may be forced into engagement with the bead 20^b. The thumb nut 24 is provided with an external central depression 24^a of 105 sufficient size to receive a head 23^a with which the bolt 23 is provided. The head 23^a prevents the thumb nut from being entirely removed from the bolt 23, but the depression in the thumb nut allows the same to be 110 unscrewed to a sufficient extent to release the bead 20^b from the groove 21^a of the clamp. It is proposed to employ as many of these pivoted clamps as may be found necessary. 115

Having thus described our invention what we claim as new and desire to secure by Letters Patent is:

1. A receptacle including an outer jacket and a removable shock insulated inner 120 vitreous container having as a part thereof a heat insulating body and the shock insulating means.

2. A receptacle, including an outer jacket, a vitreous container and an inner jacket, 125 said inner jacket being composed of a yieldable substance.

3. A receptacle, including an outer jacket, an inner container of frangible material, an inner jacket, and a shock insulating dia- 130

- phragm disposed between said container and said inner jacket, said container, said inner jacket and said diaphragm being removable as a unit from the outer jacket.
5. 4. A receptacle, including an outer jacket, an inner frangible container, a collar secured to said container, a shock insulating diaphragm secured to said collar, and an inner jacket secured to said diaphragm, the container, the collar, the diaphragm and the inner jacket being removable as a unit from said outer jacket.
10. 5. A receptacle including an outer jacket, an inner frangible container, a shock insulating diaphragm, an inner jacket and a reinforcing and retaining ring, the container, the diaphragm, the inner jacket and the ring being removable from said outer jacket.
15. 6. A receptacle including an outer jacket, a unitary shock and heat insulated inner frangible container, and a reinforcing ring disposed within said outer jacket.
20. 7. A receptacle including an outer jacket, a unitary shock and heat insulated inner frangible container, and a reinforcing ring disposed within said outer jacket, and a reinforcing band encircling said outer jacket.
25. 8. A receptacle including an outer protective jacket, an inner jacket, a container and shock insulating means, the inner jacket, the container and the shock insulating means constituting a removable unit.
30. 9. A heat insulated receptacle including an outer protective jacket, an inner jacket, a container and shock insulating means additional to the container and inner jacket for uniting the inner jacket and the container.
35. 10. A receptacle including an outer jacket inclosing a removable unitary shock insulated frangible container.
40. 11. A heat insulated receptacle including an outer jacket inclosing a removable unitary shock insulated frangible container.
45. 12. An insulated receptacle comprising an outer protective jacket and a removable insulating unit, said unit including a jacket and a container, said jacket and container being united at their upper ends by a shock insulating diaphragm closing the space between them.
50. 13. An insulated receptacle comprising an outer protective jacket and a removable insulating unit, said unit including a jacket and a container, said jacket and container being united by a shock-insulating diaphragm, the space between the container and the jacket containing heat insulating material.
55. 14. An insulated receptacle comprising an outer protective jacket and a removable insulating unit, said unit including a jacket and a container, said jacket and container being united by a shock insulating dia-
- phragm, the space between the container and the jacket containing heat insulating material, the insulating unit being removable through the top of the outer protective jacket.
60. 15. A receptacle including a protective jacket, a removable inner jacket, insulating material within said inner jacket, a container resting against said insulating material, and shock-insulating means for holding said insulating material within the space between the inner jacket and the container.
65. 16. A receptacle including a protective jacket, and a composite insulating unit comprising an inner jacket and a frangible container flexibly united to each other.
70. 17. A heat insulated vessel having an insulated corkage unit, said unit having a sheathing, a protecting cap and insulating material maintaining said sheathing and protecting cap out of contact.
75. 18. A heat insulated vessel having an insulated corkage unit, said unit having a lower metal sheathing and an upper metal protecting cap, said sheathing and cap being out of metallic contact.
80. 19. A heat insulated vessel having a removable corkage unit including a non-conducting substance and a sheathing, said sheathing having a flange embedded in a compressed portion of said non-conducting substance.
85. 20. A heat insulated vessel having an insulated corkage unit, said unit having a sheathing secured in a compressed portion of said non-conducting substance, a protecting cap having a flange encircling said non-conducting substance, and a flanged ring secured to said flange for retaining said non-conducting substance under compression.
90. 21. A heat insulated vessel having an insulated corkage unit, said unit having a sheathing secured in a compressed portion of said non-conducting substance, a protecting cap having a flange encircling said non-conducting substance, a flanged ring secured to said flange for retaining said non-conducting substance under compression, and heat insulating material disposed within said flanged ring.
95. 22. A heat insulated vessel having a removable corkage unit including a non-conducting body having parts thereof enveloped by sheet metal, a portion of said body being circumferentially disposed to contact with the mouth of the insulated vessel.
100. 23. An insulated receptacle comprising an outer protective jacket and a removable insulating unit, said unit including a jacket and a container, said jacket and container being united at their upper end by a shock-insulating diaphragm.
105. 24. An insulated receptacle, including an outer protecting jacket, a removable shock insulated unit, said unit including a jacket, 110
110. 115
120. 125
130. 130

a frangible container, shock insulating means at the upper end of the container uniting said jacket and container, the space between said container and jacket containing shock insulating material.

25. An insulated receptacle, including an outer protecting jacket, an inner jacket and a frangible container removable with the inner jacket, shock insulating means for uniting the inner jacket to the container at its upper end and means for locking the combined inner jacket and container within the outer protective jacket.

26. A removable insulating unit adapted

to fit within an outer protecting jacket, said unit including a jacket, a frangible container, flexible shock insulating means at the upper end of the jacket uniting said jacket and container, and shock insulating material surrounding the container.

In testimony whereof we affix our signatures.
